[57] CLAIM

The ornamental design for a tool carrier, as shown and described.

DESCRIPTION

FIG. 1 is a perspective view of a tool carrier showing my new design;

FIG. 2 is a top plan view thereof;

FIG. 3 is a front elevation thereof; the rear elevation being a mirror image thereof;

FIG. 4 is a left side elevation thereof; the right side elevation being a mirror image thereof;

FIG. 5 is a bottom plan view thereof;

FIG. 6 is a sectional elevation thereof; taken along line 6—6 of FIG. 2; and,

FIG. 7 is an elevation of an individual partition thereof; shown for clarity of illustration only.
